CALIFORNIA.

TELESCOPING FINGER BOARD.

Application filed June 24, 1927. Serial No. 201,269.

An object of our invention is to simplify and consequently speed up the operations of "running in" and "coming out" of the hole with drill pipe. We do this by eliminating 5 the swinging of the bottom end of the stand to cause the top end to swing around the end of the finger-board.

With our improved finger-board the sequence of steps in racking a stand of drill 10 pipe is as follows: The stand being freed from the rest of the string, the pipe racker hooks his hand hook around it and moves the bottom end directly towards the bull wheel side of the rig, imparting sufficient 15 velocity to it to cause the upper portion to pass the finger-board, and thence directly to its position on the racking pad where the driller working in unison with him sets the pipe. The derrick man releases the extensi- 20 ble tip of our improved finger-board as soon as the pipe passes it, and when the stand is lowered into position guides it into the notch provided in the finger-board tip. The elevators are then allowed to come down to 25 where he can unlatch them, after which he places the stand in position in the stack.

The racker's first movement follows approximately the center line of the derrick floor. His operation can be divided into two 30 steps, first, a straight movement towards the side of the rig and second, guiding the pipe into position. With the usual type of finger-board his movements consist of a pull towards the rotary side of the rig followed 35 by a swing to clear the finger-board and then into position on the pad. This is a longer path requiring greater effort on his part and more time.

In "running in" the sequence of operations 40 with our improved finger-board is as follows. The derrick man leans the next stand in the notch in the tip and as the elevators pass, he latches them around the pipe. At the moment of "pick-up" the finger-board is momen- 45 tarily relieved of the reaction of the stand which enables the derrick man to telescope the tip into the stem, thus leaving a clear passage for the pipe to swing out over the hole, the lifting of the stand being uninterrupted. 50 The racker on the floor simply follows the bottom end and prevents it from swinging beyond the hole. With the usual type of finger-board the racker must, as the pipe lifts clear of the floor, give the bottom end a vigorous pull toward the rotary side of the

rig followed by a swing to clear the finger-board and then guide it over the center of the hole.

By simplifying the movements of the bottom end of the stand two further advantages 60 are gained. The first is that in racking pipe the travelling block does not swing so much, which allows the elevators to move quickly slide down the pipe within reach of the derrick man. The second is that, because the 65 stand is not subjected to a large swing, the travelling block and the upper end of the stand are wobbling less when in position over the hole, thus greatly facilitating the stabbing and screwing together of the tool joint. 70

A further object of our invention is to provide a pivoted finger-board which can be swung away from the center of the rig when not in use. This increases the clearance between the travelling block and the finger- 75 board and thus greatly reduces the hazard of these two striking and breaking the finger-board. In coming out and in running in it is advantageous to have the finger-board as close to the path described by the travelling 80 block as safety permits because this makes towards speed in these operations. For these two operations the clearance between travelling block and finger can be relatively small, because the path of the travelling block does 85 not deviate greatly from the vertical. While drilling this is not true, the travelling block following the wobbling of the Kelley or grief stem which requires greater clearance at the finger-board. 90

A preferred design of our telescoping finger-board and its application in the derrick are shown on the attached drawings, in which

Figures 1 and 2 are respectively a detailed plan and elevation of a preferred construc- 95 tion of the finger-board proper.

Figure 3 is a plan view of the derrick at the height of the derrick man's platform showing the finger-board in position.

Figure 4 is an elevation of Figure 3. 100

Figure 5 is a section of Figure 2 on the line A—A.

Referring particularly to Figure 2, 1 is a base plate which is secured to the platform 2 by the bolts 3 said bolts passing through the slotted holes 4 and through the timbers or other platform material of which the platform is fabricated. These slotted holes 4 furnish the necessary adjustment for locating the end 5 of the finger-board in proper 105 110

relation to the well hole 6. On the base plate 1 is a pin 7 which passes through an extension 46 on the sub-base 9. The function of the fixed pin 7 is to secure the sub-base 9 by means of the washer 11 and nut 10 so as to provide a pivot for the sub-base 9 and the appurtenances attached thereto. In the base plate 1 are holes 8, said holes matching holes 47 in ears 49 when the relation between the base plate and the sub-base is as shown in Figures 1 and 2, thereby permitting pins 12 to be inserted in these holes, restraining the sub-base from pivoting about pin 7. The finger-board, when used to stack pipe 15 against, is still farther strengthened against pivoting by the brace 45 rigidly secured to platform 2 by bolting or other means and so arranged that it reacts against the stem 17 approximately as shown. Attached to pins 12 and sub-base 9 are chains 13, the purpose of said chains being to prevent pins 12 from becoming lost or falling when the finger-board is swung into position 14.

The sub-base 9 has a cap 15 secured to it by bolts 16, said bolts clamping the stem 17 firmly between the cap 15 and sub-base 9. The stem 17 forms the principal rigid projection of the finger-board. In the outer end of this stem is an annular ring 18, welded or otherwise secured to the stem 17, the opening in ring 18 forming one guide for the extensible tip 19 which slides therethrough. In the inner end of tip 19 is a circular ring 20, said ring being part of the tip 19. The outside diameter of ring 20 is sufficiently smaller than the inside diameter of stem 7 to permit an easy sliding fit therein. The surface 21 of ring 20 is spheroid in shape to permit the use of ordinary pipe for the stem 17. Secured to the inner end of tip 19 is a rod 22, this rod being approximately radially centered in tip 19 by a cylindrical block 23, and both rod and block restrained in place by pin or rivet 24. Rod 22 passes through an aperture 25 in the cylindrical block 26, said block being secured in stem 17 by the pin or set-screw 27. On the opposite end of rod 22 a yoke 28 is secured by a threaded connection or in other suitable manner. A coil spring 29 encircles rod 22 between blocks 26 and the inner end of the tip 19 pressing against block 23. The length of this spring is such as to return the tip 19 to its extended position.

The movement of the finger-board tip 19 is obtained by the bell crank 30, this bell crank having a fixed center rotating on pin 31, said pin being carried in a forked arm 32 which is secured to cap 15 by bolts 33. The free end 34 of the bell crank 30 has a circular eye or other means suitable for fastening to a rope wire cord. The rod end 35 of the bell crank 30 has a slotted hole 36 fitting over a pin 37 secured in yoke 28 by means not shown.

55 The rope 37 secured to end 34 of the bell

crank passes over sheaves 38 and 39, these sheaves being secured to the derrick by means not shown and so located as to guide the rope free from any obstructions and to bring its free end 40 where it will be most convenient for the derrick man to grasp.

The derrick man finds it necessary to place one foot on the finger-board during part of his duties, so to provide a suitable foothold the U plate 41 is welded or otherwise secured to stem 17. The upper surface 42 of plate 41 is wickered, knurled or otherwise roughened so as to decrease the possibility of the derrick man slipping.

The possibility of the travelling block, 80 swivel, or other lifting equipment catching on the finger-board is ever present. To reduce this hazard by preventing the finger-board from falling should such an accident occur, the safety chain 43 is secured to sub-base 9 by an eye bolt 44, the other end of chain 43 being securely fastened to the derrick at some convenient point by any suitable means not shown.

The mechanical operation of our improved 90 finger-board is as follows. The derrick man pulls downward on the end 40 of rope 37 consequently causing the bell crank 30 to rotate about its fixed center 31, this rotation causing the end 35 of the bell crank to move 95 through an arc, carrying with it the yoke 28, rod 22 and finger tip 19. The spring 29 is compressed during this movement, storing enough energy to quickly return the tip 19 to its extended position when the derrick 100 man relieves the pull on the rope.

Though we have described in the foregoing specification a complete embodiment of our invention, we do not limit ourselves to any specific mechanical design, our invention 105 being limited solely by the attached claims.

We claim as our invention:

1. In a finger-board in combination with a well-drilling derrick, a substantially rigid stem attached to said derrick and a retractile 110 extension of said stem.

2. In a finger board in combination with a well-drilling derrick, a substantially rigid stem attached to said derrick and pivoted at its fixed end for horizontal movement only, 115 and a retractile extension of said stem.

3. In a finger-board in combination with a well-drilling derrick, a substantially rigid stem attached to said derrick, a retractile extension of said stem and means for retracting 120 said extension.

4. In a finger-board for well-drilling derricks, a stationary base, a substantially rigid stem pivotally attached to said base for horizontal movement only, and a retractile extension of said stem. 125

5. In a finger-board in combination with a well-drilling derrick, a base-plate slidably attached to the derrick, means for locking down said base-plate at any point in its 130

travel, a substantially rigid stem pivotally attached to said base-plate for horizontal movement only, and a retractile extension of said stem.

5 6. In a finger-board in combination with a well-drilling derrick, a base-plate attached to said derrick and a substantially rigid stem pivotally attached to said plate for horizontal movement only, means for limiting the pivotal movement of said stem, and a retractile extension of said stem.

10 7. In a finger-board in combination with a well-drilling derrick, a substantially rigid tubular stem attached to said derrick, a re-
15 tractile extension mounted within said stem, mechanical means for retracting said extension, and a spring in compression for return-

ing said extension to its extended position.

8. In a finger-board in combination with a well-drilling derrick, a substantially rigid 20 tubular stem attached to said derrick, a substantially rigid extension slidably and concentrically mounted in said stem, means for limiting the outward movement of said extension, mechanical means for withdrawing 25 said extension into said stem and a spring in compression within said stem for returning said extension to its extended position.

In witness that we claim the foregoing, we have hereunto subscribed our names this 15th 30 day of June, 1927.

GEORGE E. FENTRESS.
